UNITED STATES PATENT OFFICE.

ROBERT WALTER ST. CLAIR AND JOSEPH R. IRVIN, OF CLYMER, PENNSYLVANIA,
ASSIGNORS TO NATIONAL AND LOCAL ADVERTISING COMPANY, INCORPORATED,
OF INDIANA, PENNSYLVANIA, A CORPORATION OF PENNSYLVANIA.

ADVERTISING APPARATUS.

Application filed April 16, 1924. Serial No. 706,959.

To all whom it may concern:

Be it known that we, ROBERT WALTER ST. CLAIR and JOSEPH R. IRVIN, citizens of the United States, and residents of Clymer, in the county of Indiana and State of Pennsylvania, have invented certain new and useful Improvements in Advertising Apparatus, of which the following is a specification.

Our invention relates to improvements in advertising apparatus and it consists of the constructions, combinations and arrangements herein described and claimed.

An object of the invention is to provide an advertising apparatus containing a plurality of display frames occupying separate compartments, there being continuously movable means which periodically transfer a display frame from one compartment to another until a complete turnover has ultimately resulted.

Another object of the invention is to provide an advertising apparatus having the continuously travelling lug or lugs for the purpose of periodically transferring a display frame from one compartment to another, there being a number of such frames arranged in packs in a plurality of compartments standing on edge.

A further object of the invention is to provide an advertising apparatus of the nature stated having spring levers which continuously exert pressure on the frame backs in the several compartments for the purpose of moving them toward that side of the compartment which constitutes the exit.

Another object of the invention is to provide an advertising apparatus containing a pair of continuously moving lugs which alternately function to push the foremost one of a stack of display frames down from one compartment and the foremost one of another pack of frames up from the compartment to which the foregoing frame was supplied, the transposition or circulation of frames being continuous until the apparatus is stopped.

Another object of the invention is to provide a novel switch arrangement in the lighting circuit which is automatically operated by a transient frame to extinguish

the light on that particular side until this frame comes to rest whereupon the current is switched on.

Other objects and advantages will appear in the following specification, reference being had to the accompanying drawings, in which

Figure 1 is a perspective view of the improved advertising apparatus mounted on the side of a building.

Figure 2 is a similar view showing the apparatus on the opposite side and illustrating how signs are displayed on both sides of the apparatus.

Figure 3 is a vertical section of a portion of the cabinet, a certain veneer strip being removed to reveal the mechanism of the spring levers.

Figure 4 is a vertical section on the line 4—4 of Figure 1, the aforesaid veneer strip being in place in this instance.

Figure 5 is a detail section of one of the electric switches.

Figure 6 is a diagrammatic perspective view of portions of the apparatus particularly illustrating the construction and operation of the lighting circuits.

Figure 7 is a vertical section confined solely to illustrating the arrangement of one of the continuously moving chains.

Figure 8 is a detail section taken substantially on the line 8—8 of Figure 4 illustrating the manner of supporting the upper shaft.

Figure 9 is a horizontal section taken substantially on the line 9—9 of Figure 4.

Figure 10 is a detail enlarged section which may be read in connection with Figure 7, illustrating the action of the cams in displacing the chain lugs so that a display frame may be released.

Figure 11 is a detail section taken through the bottom of the cabinet to illustrate the motor drive.

In carrying out the invention provision is made of a cabinet 1 including ends 2 and 3, a bottom 4 and side doors 5 and 6. The cabinet may in practice be placed wherever desired, but the drawings show it fastened to the side of a building, use being made of a bracket 7 to furnish one of the supports.

The manner of building and supporting the cabinet are immaterial.

Situated inside of the cabinet 1 is a pair of chains 8 and 9 (Figs. 8 and 9) which respectively run over pairs of sprockets 10 and 11 (Figs. 4 and 7) on upper and lower parallel shafts 12 and 13. A motor 14 (Fig. 11) furnishes the driving power. The motor belt 15 drives the sheave 16 on the counter shaft 17 which carries a worm pinion 18 to drive the worm gear 19 on the lower shaft 13.

A housing 20 encloses the worm pinion and gear so that these parts may be packed in grease for proper lubrication. The prime mover of the apparatus may be other than an electric motor. The manner of transferring power from the counter shaft 17 to the shaft 13 may be other than gears, for example, friction disks, pulleys and belts, etc.

Each of the chains 8 and 9 carries a lug 21 for the purpose of pushing display frames downward from the upper compartment and upward from the lower compartment. All of the frames 22 are identical in construction. They are divided into a plurality of packs, two being illustrated in the drawings. The frames in the upper pack are stood on edge upon a partition 23 while the frames in the lower pack are stood on edge upon the base 24.

The partition 23 and base 24 roughly define spaces 25 and 26 which are hereinafter known as upper and lower compartments. The lugs 21 are in horizontal alignment (Fig. 8) so that both corners of the display frame may be engaged at the same time, and that the frame may be moved uniformly. Each of the lugs is made alike. The description of the construction of one will answer for both. Upstanding lugs 27 are connected by a relatively long metallic link 28 which keeps them properly spaced and sufficiently rigid. The lowermost pin has the sole duty of pushing the display frames from one compartment to the other. The link 28 is longer than the links of the chain by which the lug is carried, it extending approximately over two chain links as shown in Fig. 10.

Each of the two sets of sprockets and chains occupy and run in suitably formed recesses 29 and 30 in the respective ends 3 and 4. This places them substantially level with the interior surfaces of the sides. Inasmuch as the ends of the display frames 22 contact and rub against the inside of the ends to a considerable extent, it is obviously necessary to countersink the chains so that the frames may have all required freedom. This is particularly necessary when a transfer from one compartment to another occurs.

Each of the display frames 22 has a slit

along the top rail so that a card 31 may be inserted as shown in several views. The card will contain advertising matter on both sides, or if desired, two thin cards, each separately printed on one side may be slipped in back to back. Although the frames are shown as particularly adapted to display printed advertisements it seems quite obvious that other matter such as will readily lend itself to be fixed in a frame may be exhibited or displayed.

In order that the packs of frames may be moved toward the exit sides of the respective compartments use is made of spring levers 32 and 33, these being provided either in pairs or singly as respectively indicated in Figs. 3 and 4. Each of the levers is exactly alike. A pin 34 provides the pivot for the lever. A spring 35, attached between the outer end of the lever and a suitable stud 36, tends to pull the opposite and inner end of the lever into engagement with a stop 37 but in any event keeps the free end against the outermost one of the adjacent pack of frames. The free end of each lever is rounded, and engages the vertical side of the frame.

Each cabinet end 2 and 3 carries sets of spring levers so that the discharging pressure on the frames may be uniform. The levers 32 and 33 work reversely to each other; the levers 32 yield upwardly while the levers 33 yield downwardly. This is to agree with the direction of movement of the frames. Each of the frame packs is pressed over against a furring strip 38 and 39. It is along these strips that the outermost frames at the exit ends of the compartments 25 and 26 are slid when the lugs 21 come around in pushing position.

The respective furring strips are recessed at 40 and 41 to make room for the outward bowing of the chains when the lugs 21 ride over cams 42 and 43 for the purpose of disengaging the lugs from the frames. These recesses are covered by strips 44 and 45 of suitable veneer material, not only concealing the recesses but also covering the various spring levers. In order to permit freedom of motion of the levers they may either be partially recessed in the furring strips or the veneer strips may be slightly set off by interposed supports. Recesses 46 are shown in order to illustrate one modification.

Suitable bearings support the shafts 12 and 13 at the ends. These bearings may consist of balls 47, running between a groove 48 and a sleeve 49 at each shaft end. The ends of the bearings are covered and concealed by caps 50. The manner of supporting the shafts may be other than that shown, some suitable ball bearing being preferable however.

Electric lamps 51 and 52 illuminate the display frame from opposite sides, reflec-

tors 53 throwing the light downward upon the printed type when advertising matter is displayed. These lamps are lighted only when the display frame comes to rest. They are extinguished while the frames are in motion during transit from the compartment 25 to the compartment 26 and vice versa. Only one lamp is extinguished at a time because only one frame moves at one time.

This controlling of the electric lamps is accomplished by switch arms 54 and 55. These arms and the switches which they control are provided in duplicate on each side so that each side has a pair of electric switches as suggested by corresponding reference characters in Fig. 6. All of the switches are alike and the description of one will suffice for all.

In Figure 5 the switch arm 55 projects through the slot 56 of the switch casing 57. This casing houses the switch mechanism on the porcelain or other insulating base 58. The casing is preferably made removable. The arm 55 is pivoted at 59. A frame 60 fastened at one end and attached to the inner end of the switch arm at the other pulls up on the switch arm and keeps it in engagement with a contact 61 representing one terminal of an electric circuit. The other terminal has connection with the switch arm through the spring 60. The two terminals are represented at 62 and 63. An upward movement of the arm 55 (dotted lines) breaks the circuit at the contact 61 so that the lamp 52 on that side is extinguished. This upward movement of the arm 55 occurs when a frame 22 is transferred from the lower to the upper compartment.

A motor 14 provides the driving power for the apparatus. Current is supplied by the positive and negative leads 65 and 66 (Fig. 6) the former of which having a suitable snap switch 67 so that the motor can be stopped and started. Wires 68 and 69 in parallel with the main leads convey current to the lamps 51 while wires 70 and 71 in parallel with the main leads supply current to the lamp 52. These pairs of wires constitute shunt circuits which are individually controlled by the pairs of switches already mentioned. The contacts 72 of the switches 54 are connected together by a wire 73 and the arms 54 themselves are connected by a wire 74. Similarly, the contacts 61 of the arms 55 are connected by a wire 75, while the arms themselves are connected by a wire 76.

The purpose of thus providing duplicate switches at opposite ends of the display frame and connecting them together electrically is to insure that there shall be at least one operable switch in the event something should go wrong with the other.

In order that the packs of frames may readily slide across the partition 23 and base 24 provision is made of bearing strips or slides 77 and 78. The top of the cabinet is suitably shaped to contain a clock 79 70 which has faces on opposite sides of the cabinet.

The operation may be readily understood from the following additional description. All of the display frames 22 are first filled 75 with sign cards 31 in the event that the apparatus is used for display advertising matter. For the first purpose the top rails of the frames are slit so that the cards may be slid in. Cards are either printed on both 80 sides so that only one need be inserted, or two cards, printed on one side, can be inserted back to back.

The display frames are arranged in two packs approximately evenly divided and 85 stood on edge upon the partition 23 and base 24 as clearly shown in Figure 4. Other than this the frames have no support, it being noticed that there is an absence of means for suspending the frames from the 90 chains, or other such expedients as commonly adopted. It has been stated that the partition 23 and base 24 provides the sole support for the frames. An additional 95 support, but of a wholly different nature, is afforded by the furring strips 38 and 39 at opposite sides of the advertising cabinet. The frames in the upper pack are firmly 100 pressed to the left (Figures 3 and 4) against the furring strip 38 by the spring lever 100 32, while the pack of frames in the lower compartment are firmly pressed toward the right against the furring strip 39 by the spring lever 33. The particular and outermost frames next to the furring strips are 105 in positions to be slid down or up as the case may be, and thereby undergo a transfer from one compartment to another. It is in this manner that continuous changes 110 of display occur.

The electric motor 14 drives the endless chains 8 and 9 continuously. These run over pairs of sprockets 10 and 11 at the top and bottom respectively. Each chain carries a single lug 21. The lug should be in horizontal alignment so as to evenly contact the frames and push them in a rectilinear direction.

Assume that the lugs 21 have come around and are about to engage the outermost frame 22 in the upper compartment 25 (see Figs. 3 and 4). As soon as the lugs engage the upper corners of the frame a forcible downward push commences, and inasmuch as the arm 54 of an electric switch is disposed immediately below that frame an opening of the switch promptly occurs to extinguish the lamp 51 (Fig. 6) immediately that movement of the frame starts. The pushing of the frame occurs under the tension of the 130

spring arms 32 because these are pressed against the upper pack by the spring 35 (Fig. 3).

Pushing of the frame in question continues until the lugs 21 reach the cams 42. These cams are situated in proper positions to make the lugs ride out (Fig. 10) and release the frame when it comes into registration with the lower pack. Spring levers 33 then operate to push the entire lower pack over against the right furring strip 39, the extreme right frame thus being in position to be pushed up toward the lugs 21 move along the return side of the chains.

It is to be observed that there is considerable space between the base 24 and the lower shaft 13. The lugs 21 consume sufficient time in traversing the part of the chains thus represented to give the observer of the apparatus sufficient opportunity to read the signs displayed. As soon as the lugs reach the bottom of the right frame in the lower pack an upward push results. The switches 55 are operated to open the circuit of the lamps 52 whereupon this lamp is extinguished and the illumination of the signs ceases until the complete transfer has been made. As soon as the frames, whether they be going down or up, pass the respective switch arms the respective circuits of the lamps 51 and 52 are again closed and the illumination of the sign again occurs when the change has been made.

While the construction and arrangement of the improved advertising apparatus as herein described and claimed is that of a generally preferred form, obviously modifications and changes may be made without departing from the spirit of the invention or the scope of the claims.

We claim:

1. Apparatus of the character described comprising a plurality of display frames, means defining compartments which are occupied by said frames when divided into packs, continuously moving means periodically engaging a frame in each pack to push the frames from one compartment to another thereby causing a circulation of the frames on a step by step order, means to illuminate the outermost frame, and means to extinguish the illuminating means on a particular side as soon as the frame starts to move and continuing during the transit of the frame.

2. Apparatus of the character described comprising a plurality of display frames, means defining compartments including a partition and base upon which the frames stand when separated into packs, abutments including furring strips at one side of each frame pack, means at the opposite side of each frame pack to firmly press the pack into engagement with the respective furring strips, and continuously moving means pe-

riodically engaging an outermost frame of each pack and forcibly moving it along the adjacent furring strip to the next compartment thereby causing a step by step circulation of the frames.

3. Apparatus of the character described comprising a plurality of display frames, means defining compartments including a partition and base upon which the frames stand when separated into packs, abutments including furring strips at one side of each frame pack, means at the opposite side of each frame pack to press the pack into engagement with the respective furring strips, continuously moving means including a chain extending substantially full length of said compartments and carrying means periodically engaging an outermost frame of each pack and moving it along the adjacent furring strip to the next compartment thereby causing a step by step circulation of the frames, and means for displacing said continuously moving means to disengage said carried means from the frame when the objective compartments have been reached.

4. A device of the character described comprising means defining compartments including a partition and a base, a display frame occupying each compartment standing on the partition and base respectively, means continuously exerting pressure against each frame, abutment means including furring strips against which said frames are pressed thereby causing them to tend to remain in position, and continuously moving means first engaging a frame in one compartment to push it along a furring strip out of said compartment past said partition into the other compartment then subsequently engaging the first frame in said other compartment and pushing it along the second furring strip past the partition to the first compartment.

5. Apparatus of the character described comprising a plurality of display frames divided into two packs, a partition separating the packs and constituting a part of compartments in which the frames are situated, means continuously pressing upon the frames from opposite sides so that opposite frames are projected beyond the edges of the partition, continuously moving means for engaging the upper edges of the projecting frames and forcibly pushing them past said partition from one compartment to the other at intervals, while said pressing means continues its pressure thereagainst and means for disengaging the pushing means from a particular frame when the intended change of location has been effected.

6. Apparatus of the character described comprising a plurality of display frames divided into two packs, a partition dividing the packs and constituting part of compart-

ments occupied by said packs, levers situated at diametrically opposite sides of the two packs, springs so connected to the levers and actuating them as to press against the packs

5 in opposite directions causing the outermost frames at diagonally opposite sides to project beyond the edges of the partition, continuously moving means including a lug engaging the projected frame of one compartment and pushing it past the partition into the other compartment, means to displace the lug when said other compartment is reached so that the lug may continue its movement and ultimately engage the other projected frame to move it past the partition into the first compartment, and to again displace the lug and free the frame when said first compartment is reached.

7. Apparatus of the character described comprising a plurality of display frames divided into two packs, a partition dividing the packs and constituting a part of compartments occupied by the frame packs, a furring strip in spaced relation to each opposite side edge of the partition leaving a frame passage, means including spring levers pressing against the frame packs from diagonally opposite sides to press diagonally opposite frames into said passages and against the furring strips where they are held, means including a continuously traveling lug for pushing the frames in said passages from one compartment to the other against the resistance of said spring levers, and means including cams situated adjacent to said edges of the partition for properly displacing the lug to free the frames upon reaching the respective compartments.

8. Apparatus of the character described comprising means providing a pair of compartments including a base and a separating partition, a plurality of display frames divided into packs and stood on edge upon the partition and base respectively, means pressing against the packs to advance them toward diagonally opposite sides of the partition, abutment means including furring strips against which the most advanced frames are thrust, a lug to engage the advanced frames at intervals and transfer them in respect to the compartments, means to displace the lug from the frames when the respective compartments are reached, continuously moving means including a chain by which the lug is carried, and a shaft having sprockets by which the chain is operated, one of the shafts and sprockets being situated a considerable distance below the base to suitably separate the interval between the end of the transfer of one frame and the beginning of the transfer of another.

9. Apparatus of the character described comprising a plurality of display frames

divided into packs, means defining compartments for the packs including a partition and a base on which the respective packs stand one above the other, means to press against the packs from diagonally opposite sides to advance the oppositely outermost frame beyond the edges of the partition, abutments including furring strips against which said advanced frames are pressed, said strips having cut out portions providing recesses adjacent to the edges of the partition, continuously moving chains having lugs in parallelism to engage the advanced frame and push it past the partition from one compartment to another, and a cam situated at each edge of the partition to displace the lugs into said recesses and from engagement with the particular frame when that frame has reached its destination.

10. Apparatus of the character described comprising a cabinet, a base and a partition erected in the cabinet to roughly define two compartments, one above the other, a plurality of display frames separated into packs supported on edge upon the partition and the base, means pressing on the packs from diagonally opposite sides to advance opposite ones of the frames beyond the edges of the partition, continuously moving chains having lugs to engage the advanced frames and push them from one compartment to the other, an electric lamp situated at each side of the frame packs to illuminate the outermost frames, electrical circuits embracing the lamps, and separate switches having arms directed toward the partition from opposite sides and in the path of the advancing frames, causing an operation of a particular switch to open a circuit upon the beginning of movement of a frame, said circuit remaining open to extinguish the respective lamps until the destination of the frame is reached.

11. Apparatus of the character described comprising a plurality of display frames arranged in a pack, means pressing against the pack from one side, abutments against which the pack is pressed, continuously movable means arranged to engage the advanced frame and push it along the abutment means out of the pack, an electrical circuit including a lamp for illuminating said advanced frame while stationary, and switch means which is operated when the advanced frame begins to move to break the circuit and extinguish the lamp, said switch means being provided in duplicate beneath said advanced frame adjacent to opposite edges insuring the operation of the lamps even should one of the switches fail to function.
